UNITED STATES PATENT OFFICE.

WILLIAM C. STEVENS, OF AKRON, OHIO, ASSIGNOR TO PIERCE WRAPPING MACHINE COMPANY, OF CHICAGO, ILLINOIS, A CORPORATION OF ILLINOIS.

ADJUSTING MEANS FOR WRAPPING-MACHINES.

1,241,678.

Specification of Letters Patent.

Patented Oct. 2, 1917.

Original application filed August 19, 1912, Serial No. 715,745. Divided and this application filed October 15, 1915. Serial No. 56,076.

To all whom it may concern:

Be it known that I, WILLIAM C. STEVENS, a citizen of the United States, and a resident of the city of Akron, in the county 5 of Summit and State of Ohio, have invented certain new and useful Improvements in Adjusting Means for Wrapping-Machines; and I do hereby declare that the following is a full, clear, and exact description of the same, reference being had to the accompanying drawings, and to the numerals of reference marked thereon, which form a part of this specification.

This application constitutes a divisional 15 application of my co-pending application for patent for "wrapping machines", filed August 19, 1912, Serial No. 715,745.

This invention relates in particular to the specific adjusting mechanism for the 20 supporting and driving rollers of a wrapping machine adapted to apply a spiral wrapping or covering strip such as paper about an article moved through the eye of a shuttle, such as annular bodies, lengths of 25 pipe, or the like.

It is an object therefore of this invention to provide an improved type of adjusting mechanism for the supporting and driving rollers of a high speed wrapping machine.

It is also an object of this invention to construct a wrapping machine for the purpose specified having a large range of adjustment to adapt the machine for wrapping annular bodies of different sizes permitting the elements of the machine to be quickly and readily adjusted to accommodate an article therein.

It is also an object of this invention to provide a means for positively supporting 40 and rotating an article to be wrapped and for adjusting said supporting and rotating means relatively to one another and to the wrapping machine.

It is finally an object of this invention to 45 construct a wrapping machine provided with an improved form of adjusting means for adjustment of the supporting and driving rollers on which an article is placed before wrapping.

The invention (in a preferred form) is 50 illustrated in the drawings and hereinafter more fully described.

On the drawings:

Figure 1 is a side elevation of a wrapping machine embodying the principles of my 55 invention.

Fig. 2 is a central transverse section thereof with parts shown in elevation.

Fig. 3 is a top plan view of the machine with parts in section and parts omitted. 60

As shown in the drawings:

The reference numeral 1, indicates a relatively low base or table supported upon a suitable frame or legs 2, and having a central longitudinal slot therethrough. Journaled transversely of said table on the top thereof is a driving shaft 3, having at the outer end thereof tight and loose belt pulleys 4 and 5, respectively, adapting the shaft to be driven from any suitable source 65 of power.

Mounted upon said table at one side of said central slot, is an upright crescent-shaped frame 6, which, as shown, is rigidly bolted to said table with the arms of the 75 crescent directed upwardly and outwardly or forwardly as clearly shown in Fig. 1. Rigidly secured upon said driving shaft 3, is a belt pulley 7, having a double peripheral flange 8, projecting circumferentially 80 therearound affording a grooved periphery to receive a belt 9, trained therein.

Journaled longitudinally of the table on each side of said belt pulley 7, in bearings 10 and 11, are shafts 12 and 13, each having eccentric portions extending through sleeves 14, and each sleeve provided with upwardly directed front and rear bracket arms 15 and 16, respectively. Said sleeves and eccentrics are normally held to rotate together by 90 means of set screws 37. Journaled through the upper ends of each pair of bracket arms 15 and 16, are shafts 17, having grooved rollers 18, rigidly secured thereon. Said shafts 17, at their rear ends are provided 95

with sprocket wheels 19, about which are trained sprocket-chains 20, which are also trained about sprocket wheels 21, rotatably mounted on the ends of the respective shafts 12 and 13. Integrally or otherwise rigidly 100 connected with each of said sprocket-wheels 21, are worm gears 22, also rotatable on said respective shafts 12 and 13, and each in mesh with one of two worms 23, on said

driving shaft 3, so that rotation of said drive shaft 3, acts through the medium of said respective worms and worm gears and sprocket wheels and chains to rotate the 5 grooved feed rollers 18.

Means are provided for adjusting said feed or advancing rolls toward and away from one another. For this purpose, as shown, a downwardly directed arm 24, is 10 provided on each of said sleeves 14, and carried in the lower end of each of said arms is a nut 25, through which extends a screw shaft 26, which is pivotally mounted in a bearing 27, on the frame or table. Rotation 15 of one of said screw shafts acts on the nut 25, to swing the corresponding advancing or feed roll outwardly or inwardly, dependent upon the direction of rotation, thus enabling either or both of said advancing 20 and feed rolls 18, to be adjusted to the most efficient position for supporting and rotating or advancing the article to be wrapped. Outward adjustment of said feed rolls obviously permits the supported object to be 25 supported somewhat lower in the machine, while inward adjustment of the feed rolls supports said articles higher in the machine.

Mounted on said grooved driving pulley 7, with its flat periphery fitting in the 30 groove in the periphery of said driving pulley is an annular shuttle 28, which is mounted vertically transversely of the tire or other body to be wrapped. Journaled on the forward arm of the crescent frame 6, at 35 its extremity is a grooved pulley 29, and on the other or rear arm of said crescent frame 6, is another grooved pulley 30. Said grooved pulleys 29 and 30, receive the periphery of the annular shuttle 28, in the 40 grooved peripheries thereof while said shuttle is supported on the grooved driving pulley, said shuttle thus being engaged at three points at substantially equal distances apart, permitting the shuttle to rotate freely 45 therewith and therebetween. The belt 9, trained about the grooved driving pulley 7, is also trained about the grooved pulley 30, and downwardly around a part of the periphery of the shuttle 28, and then over the 50 pulley 29, thereby operating to rotate the shuttle. A hinged section 31, is provided in said shuttle 28, to permit opening thereof to receive an article to be wrapped inserted therein, and suitable locking means is 55 provided to lock the same in closed position, the details of which, however, since they form no part of this invention, being omitted from the description.

A reel of paper 32, is mounted at a convenient point upon the shuttle 28, opposite the hinged section 31, of the shuttle, and rotates around with the shuttle, feeding the paper upon an article being wrapped. Mounted upon the table at the rear of the 65 shuttle and rigidly secured in a bracket 33,

is a standard 34, and adjustably secured on said standard in any suitable manner is a yoke 35, having journaled between its arms an upright roller 36, as shown in Fig. 1, against which the top of the tire or other 70 annular body to be wrapped rests and travels during the wrapping operation. The adjustment according to the size of the body to be wrapped is accomplished by adjusting the advancing or feeding rollers 18, inwardly or 75 outwardly toward or away from the shuttle by means of the screw shafts 26. The yoke 35, carrying the roller 36, is then adjusted upwardly or downwardly on the standard and outwardly or inwardly as required to 80 properly support the top of the annular body. The driving belt, not shown, is then shifted to the tight pulley on the drive shaft 3, causing the shuttle to be rotated at a relatively high rate of speed while the tire or 85 other annular body supported in the machine is rotated by means of the advancing rolls 18, at a sufficient rate to give the desired lead for the material wound upon the tire or annular body while the paper or 90 other wrapping material 32, is drawn from the shuttle around the article. If it is desired to vary the tension upon the sprocket chains 20, by which the rollers 18 are driven, this is readily accomplished by 95 release of the respective set screws 37, after which the sleeves and mechanism supported thereby is partially rotated relatively of the eccentric portion of the shaft which serves to elevate or lower the shafts carrying 100 the sprocket wheels 19. The set screws are then tightened to prevent relative movement of the sleeves and eccentrics. Inasmuch as the eccentrics and sleeves normally move together when adjusting the screw shaft 26, 105 the sprocket wheels are held in unvarying relation to keep the proper tension on the chain.

I am aware that the various details of construction may be varied through a wide 110 range without departing from the principles of my invention and I therefore do not purpose limiting the patent granted otherwise than necessitated by the prior art.

I claim as my invention:

1. In a device of the class described a frame, a table top thereon, bearing members secured on said table top, an adjusting shaft journaled therein, an eccentric portion on said adjusting shaft, a sleeve journaled on the eccentric portion of said adjusting shaft, means holding said sleeve and eccentric portion to rotate together or relatively of each other, arms connected to said sleeve, a roller rotatably mounted at the upper ends of said arms, a depending arm on said sleeve, a pivoted nut on the end of said depending arm, a pivotally mounted screw shaft engaging the pivoted nut of the depending arm of 120 said sleeve acting when rotated to actuate 125

said sleeve to tilt said roller, and driving means for the roller in any tilted position.

2. In a device of the class described a frame, a table top thereon, bearings secured upon said table top, an eccentric shaft journaled in said bearings, a sleeve secured on said eccentric shaft, normally rotatable therewith and also rotatable relatively thereof, arms on said sleeve, a roller rotatably mounted in the ends thereof adapted to be tilted when said sleeve is rotated, driving means for said roller rotatably mounted on the end of said eccentric shaft, and driving connections between said driving means and said roller, said eccentric shaft when adjusted relatively of the sleeve, serving to vary the tension on said driving connections.

3. In a device of the class described a frame, a table top secured thereon, bearings secured upon said table top, a shaft journaled in said bearings having an eccentric portion integral therewith, a sleeve on said shaft on the eccentric portion thereof, means adapted to secure the sleeve to the eccentric portion to turn together or to release one from the other to permit relative turning, arms secured integrally on said sleeve, a rotatably mounted roller in said arms, driving means for said roller rotatably mounted on the end of said shaft, a sprocket chain connecting said driving means to drive said roller whereby the tension of said sprocket chain may be varied by rotating said shaft to vary the position of the sleeve thereon relative to the eccentric portion of said shaft, a depending integral arm on said sleeve, a screw shaft pivotally mounted transversely beneath said sleeve, and pivoted means on said depending

arm having threaded connection with said screw shaft whereby said sleeve may be adjusted with said eccentric shaft by rotation of said screw shaft.

4. In a device of the class described the combination with a frame, of bearings mounted thereon, an eccentric shaft journaled in said bearings, a sleeve on said eccentric shaft adapted to be raised and lowered by relative adjustment between the same and said shaft, means for swinging said sleeve and said eccentric shaft comprising a screw shaft rotatably mounted transversely beneath said sleeve, and a depending arm on said sleeve operatively connected with said screw shaft, a roller supported by the sleeve and mechanism for rotating the same.

5. In a device of the class described a shaft, an eccentric portion thereon, a sleeve rotatably mounted on the eccentric portion of said shaft, a lead screw operatively connected with said sleeve to oscillate the same and said eccentric portion, a roller supported by said sleeve, driving means therefor mounted on said shaft, driving connections between said roller and said driving means, and means for adjusting said sleeve to vary the position of the sleeve and the roller supported thereby with respect to the driving means to change the tension on said driving connections.

In testimony whereof I have hereunto subscribed my name in the presence of two subscribing witnesses.

WILLIAM C. STEVENS.
